Primary Examiner — John Windmuller

(74) Attorney, Agent, or Firm — Barley Snyder

(57) **CLAIM**

The ornamental design for a clip, as shown and described.

DESCRIPTION

FIG. 1 is a front top and left side perspective view of a clip, showing the new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines shown in the Figures are included to show unclaimed subject matter only and form no part of the claimed design.

1 Claim, 6 Drawing Sheets(56)
